J. W. AYLSWORTH,
PROCESS AND APPARATUS FOR FRACTIONAL DISTILLATION AND CONDENSATION,
APPLICATION FILED NOV. 9, 1915.

1,250,760.

Patented Dec. 18, 1917.

UNITED STATES PATENT OFFICE.

JONAS W. AYLSWORTH, OF EAST ORANGE, NEW JERSEY, ASSIGNOR TO CONDENSITE COMPANY OF AMERICA, OF BLOOMFIELD, NEW JERSEY, A CORPORATION OF NEW JERSEY.

PROCESS AND APPARATUS FOR FRACTIONAL DISTILLATION AND CONDENSATION.

1,250,760.

Specification of Letters Patent.

Patented Dec. 18, 1917.

Application filed November 9, 1915. Serial No. 60,615.

To all whom it may concern:

Be it known that I, JONAS W. AYLSWORTH, a citizen of the United States, residing at East Orange, in the county of Essex and 5 State of New Jersey, have invented certain new and useful Improvements in Processes and Apparatus for Fractional Distillation and Condensation, of which the following is a specification.

10 My invention relates to a process for the fractional separation of substances having slight differences in boiling points, and to a suitable apparatus for practising such process. Ordinarily, substances of low boiling point, such as benzol, require a different apparatus, for fractional separation, from substances having a high boiling point, such as phenols, cresols, etc. By my invention, however, the same process and apparatus may be used for substances having either high or low boiling points. The process involves a combination of fractional distillation and fractional condensation, the latter being under control, so that the condensation can be regulated to take place at 15 any desired temperature within limits, which in my preferred apparatus, may be considered as 60° C. and 300° C.

The process may be described briefly as 20 consisting in evaporating the liquid to be fractionated in a suitable still and passing the distillate over a condensing surface of large capacity relatively to the evaporating surface of the still. The temperature of the 25 condensing surface is carefully regulated, so that it is equal to or slightly less than the boiling point of the fraction first to be obtained. Liquids which condense on the condensing surface are continuously returned 30 to the still and the vapor which does not condense, namely, the fraction to be separated, is passed into a cooled condensing coil and collected. The temperature of the large capacity condensing surface is then 35 increased to or slightly below the boiling point of the fraction of next higher boiling point which is to be separated, and the operation repeated until the various desired fractions have been separated.

40 The process described may be practised by the use of a horizontally disposed condensing coil mounted in a closed receptacle and connected respectively to the still and a water-cooled condensing coil for receiving

the desired fraction. The horizontal coil 55 may be heated to the desired regulated temperature by rapidly circulating oil or other heating medium through the closed receptacle and about the convolutions of a horizontal coil therein, this circulating oil being heated, or, if necessary, cooled by a heating or cooling device included in the circulating system, the heat added or abstracted being carefully regulated, preferably by automatic thermostatic means. 60 The lower loops of the convolutions of the horizontal coil are connected by return pipes to the still, so that fractions condensed in the coil will be returned to the still, these return pipes being provided with gage 70 glasses, so that operation of the system may be properly observed.

It will be observed that the method requires the use of a condensing surface or coil having relatively large capacity, namely, greater 75 than ten times that of the evaporating surface of the still, in order that substances having boiling points close together may be separated. The method also requires that the heating fluid shall be circulated rapidly 80 to keep it at uniform temperature throughout, and that regulated means be employed for adjusting the temperature of the heating fluid, this heat being independent of that produced in the still. With the apparatus 85 and process briefly described, substances having only one-half degree centigrade difference in boiling point may be effectively separated in the case of high boiling point substances, and substances having even less 90 difference in boiling point may be effectively separated when low boiling point fluids are being operated upon.

My invention may also be practised in a modified manner, by using steam as the 95 heating fluid, in place of oil or the like. In this case the pressure of the steam supplied must be such as to provide the required temperature, which can be varied as the operations change, and a sufficient flow of 100 steam about the condensing coil must be maintained.

In order that a clearer understanding of my invention may be had, attention is hereby directed to the accompanying drawing 105 forming part of this application and illustrating a preferred form of apparatus whereby the described process may be prac-

tised. In the drawing the figure represents the apparatus diagrammatically, partly in side elevation and partly in section.

Referring to the drawing, the still 1 is connected by pipe 2 to the condensing coil 3, the axis of which is horizontal. Coil 3 is contained within the closed receptacle 4, through which heated oil is circulated by means of the pump 5, which forces the oil through connection 6, heater 7 and pipe 8 into receptacle 4, the oil returning to the pump by connection 9. Vapors which are not condensed in coil 3 pass by pipe 10, into the vertical condensing coil 11 contained in the water-cooled receptacle 12. The liquid condensed in coil 11 passes through connection 13 or 13' to collecting vessel 14 or 14', connections 13 and 13' being provided with suitable valves 15 and 15'.

20 The still 1 may be steam heated as is indicated, or heated by direct fire. When substances having boiling points up to approximately 220° C. are operated on, the still is preferably heated by steam and in this case 25 the operation is suitably carried on under a vacuum as this reduces the boiling point of the substance about 70° C. The vacuum may be provided on the system by providing vessels 14 and 14' with a T connection 16 30 which leads to a vacuum pump, the branches of connections 16 being provided with suitable valves 17 and 17'.

With substances having very low boiling 35 points, such as benzol, gasoline, etc., steam is used to heat the still, but the operation is carried on under atmospheric pressure. When the system is used to operate upon substances whose boiling point is higher than that at which steam can supply the 40 necessary heat, direct fire may be used under the still.

The receptacle 4 is provided with an expansion chamber 18 for the heating oil, which chamber may be provided with a cover 19 45 for introducing the oil into the system. Chamber 18 should be of sufficient size to accommodate the oil when working at high temperatures. Pipes 20 connect the bottom loops of coil 3 with a manifold 21, pipes 50 20 passing through suitable tight openings in the bottom of receptacle 4, and manifold 21 having a trap 22, which may be provided with a pet-cock 23, and leading into the still.

55 The return pipes 20 are provided with gage glasses 24 as it is very necessary that the operation of the system should be observed. When the system is in proper operation condensed liquid will be observed 60 dripping through all of the pipes 20, except the several last ones.

Baffle plates 25, 25 are preferably positioned in receptacle 4 to extend alternately up from the bottom and down from the top 65 in order to aid proper circulation of the

heating fluid about the coils and to aid in keeping the temperature of the heating fluid uniform. For the same purpose, the capacity of pump 5 is made sufficient to insure a rapid circulation of the heating oil. 70 The heater 7 is heated by any suitable means which can be closely regulated, as for example, by a gas flame. A thermometer 26 is positioned in pipe 10, leading from coil 3, to coil 11, this indicating whether the 75 proper temperature of the fraction being separated is attained. Means for determining the temperature of the heating fluid within receptacle 4 is also provided. While this may be a thermometer, it is preferably 80 a thermostatic device 27, electrical or otherwise, which may be connected, as is indicated at 28, to the thermostat regulator 29, the function of which is to automatically regulate the heat supplied by heater 7 to 85 the circulating oil.

Any suitable form of thermostat regulator may be employed. As an example I have indicated the device 29 for controlling the flow of gas to the burner 32 of heater 90 7. This may comprise a solenoid 33, the core 34 of which is raised when circuit is completed through the solenoid and a battery 35 upon the closing of contacts in the thermostat 27. This latter may comprise 95 a pair of conducting elements connected respectively to the wires 36, 36' of the solenoid circuit 28, which elements engage each other when a desired temperature is attained by the bath in receptacle 4. When 100 contact is thus made core 34 rises and causes valve 37 to partly close the passageway 38 of the valve casing 39, thus reducing the flow of gas through pipe 40 to the burner 32. Upon a slight reduction in the temperature of the heating fluid in receptacle 105 4 thereafter the contacts of thermostat 27 separate and core 34 and valve 37 drop to open the gas passage more widely. The contacts of thermostat 27 should be adjustable, so as to make contact at different desired temperatures.

For the circulating medium, any suitable oil of low viscosity may be used. Vessel 12 may be supplied with cooling water by connection 30, overflow running out from pipe 31. A pair of collecting vessels 14 and 14' are provided, so that the system may operate continuously and one vessel be supplied with a desired condensed fraction 120 while the other is being emptied.

I am aware that it has previously been proposed to fractionally distil and condense certain substances, such as phenol, by passing the distillate over a condensing surface, 125 having return pipes leading back to the still, for condensed fractions of higher boiling points than that desired. Such systems are without flexibility or means for regulation. The novelty of my improved 130

process and apparatus chiefly consists in the use of a condensing coil, preferably a continuous spiral, having the condensing surface greater than ten times that of the evaporating surface of the still; circulating the heating fluid rapidly to keep it at uniform temperature throughout; the provision of a heating means, independent of the still, which can be regulated closely to determine quite exactly the temperature of the substances passing through the condensing coil; and the use of gage glasses in the return pipes leading from the coil back to the still. The greater the condensing surface in the horizontal coil the more effective will be the apparatus in separating liquids having close boiling points.

As has been stated, my invention may also be practised by using steam as the heating fluid. In this case the pressure in the steam generator is carefully regulated, so that the temperature required for the first fractionating operation, corresponding to that pressure, will be obtained. In this case the heater 7 is rendered unnecessary, as well as the pump 5, steam entering receptacle 4 at one end, flowing therethrough, passing out at the other end, and escaping. When a higher temperature is required for subsequent fractionating operations, the pressure in the steam line is correspondingly raised. The steam must be passed through vessel 4 at a sufficient rate of flow. Substances having boiling points varying between say 100° C. and 150° C. may be operated upon by this method; if a vacuum is used in the distilling system, as stated above, substances having higher boiling points, under atmospheric pressure, are brought within the range above indicated. Thus the boiling points of the various cresols may be brought to below 150° C. by the use of a vacuum.

Having now described my invention, what I claim and desire to protect by Letter Patent is as follows:—

1. In fractional distillation and condensation apparatus, adapted to operate on substances both of high and low boiling points, the combination of a still, a closed receptacle, 50 a condensing coil therein having its axis

horizontal, and having a condensing surface at least ten times as great as the evaporating surface of the still, a connection between said still and one end of the coil, means for condensing and collecting substances which do not condense in the coil, a connection 55 between said means and the other end of the coil, means for obtaining the temperature in said last-named connection and in said receptacle, means for leading away 60 condensed substances from the bottom loops of the coil, and a system for rapidly circulating a heating fluid through said receptacle, about said coil, comprising pipe connections, pumping means, and a heater 65 regulable to heat the said heating fluid to any desired one of several temperatures in accordance with the indication of said temperature-obtaining means, substantially as set forth.

2. In fractional distillation and condensation apparatus, adapted to operate on substances both of high and low boiling points, the combination of a still, a closed receptacle, a condensing coil there- 75 in, having its axis horizontal, and having a relatively large condensing surface in reference to the evaporating surface of the still, a water-cooled condensing coil, connections between said still and one end of said horizontal coil, and between the other end of said coil and said water-cooled coil, a system for rapidly circulating a heating fluid through said receptacle, about said horizontal coil, comprising pumping means of 80 sufficient capacity to cause such rapid circulation, a heater for the fluid, and adjustable thermostatic means, governed by the temperature of said fluid in said receptacle, for regulating the heat supplied by said heater, 90 to maintain said fluid while within said receptacle uniformly at a desired one of several desired temperatures, substantially as set forth.

This specification signed and witnessed 95 this 5th day of November, 1915.

JONAS W. AYLSWORTH.
